CUTTING ATTACHMENT FOR TUFTING WORK

Boyd N. Cagle, Hendersonville, N. C., assignor of one-half to Sidney A. Cagle, Hendersonville, N. C.

Application July 31, 1936, Serial No. 93,714

2 Claims. (Cl. 112—79)

The invention relates to a tufting attachment for sewing machines and more especially to a cutting attachment for tufting work to be used on heavy duty sewing machines.

5 The primary object of the invention is the provision of an attachment of this character, wherein in the cutting blade is pivotally held in place by a leaf spring so that said blade can be conveniently and easily removed when it is required 10 that the same be sharpened and said blade is of novel construction for coaction with a hook which is adapted to pass through the loop of the thread when carried downwardly by the needle of the sewing machine so that said loop can be 15 severed or cut by the cutting blade for tufting in the formation of pile upon a piece of work.

Another object of the invention is the provision of an attachment of this character, wherein in the mounting of the loop hook and the blade 20 is novel and unique, the blade and the hook being fastened for cooperation with each other in a simple manner so that these can be removed when the occasion requires for replacement or for conditioning as the occasion may require.

25 A further object of the invention is the provision of an attachment of this character, which is extremely simple in its construction, thoroughly reliable and effective in its operation, automatic in the working thereof, strong, durable, and 30 inexpensive to manufacture and install.

With these and other objects in view, the invention consists in the features of construction, combination and arrangement of parts as will be hereinafter more fully described, illustrated in 35 the accompanying drawing, which discloses the preferred embodiment of the invention and pointed out in the claims hereunto appended.

In the accompanying drawing:

Figure 1 is a side elevation of the attachment 40 constructed in accordance with the invention showing the blade in open position.

Figure 2 is a view similar to Figure 1 showing the blade closed.

Figure 3 is a sectional view on the line 3—3 of 45 Figure 1 looking in the direction of the arrows.

Figure 4 is a perspective view of the blade detached.

Similar reference characters indicate corresponding parts throughout the several views in 50 the drawing.

Referring to the drawing in detail, A designates generally the oscillatory member of the attachment which is in the form of a straight arm 55 having a laterally offset hub 11 at its lower end and this hub is fitted upon a stationary bolt

or rod (not shown) as built within a heavy duty sewing machine, the arm being free on this bolt or rod so as to move back and forth when operated by a bar which extends from the feed bar down to the arm and having connection therewith, the bar being also not shown.

Formed at the upper end in one side face of the arm 10 is a recess 12 in which is seated a loop hook 13 which has the bill 14 projected outwardly at a slight angle to the longitudinal axis of the 10 said arm 10. This hook 13 is separably secured to the arm 10 by a removable bolt or screw 15 which is loosely passed through the arm transversely thereof and threaded into said hook so 15 that such hook is readily detachable at will.

At the uncovered side of the hook 13 is a cutting blade 16 which tapers in one direction and in the narrow end thereof is provided a notch 17 while at the wider end is formed a beveled cutting edge 18 which is next to the bill 14, the beveled cutting edge 18 being extended for a distance of the wider end so that the heel portion 19 of such edge is blunt. At the heel corner of the blade 16 is an opening 20 for accommodating a stepped pivot stud 21 fixed to and projected inwardly from a blade leaf spring 22. This spring 22 at its lower end is detachably fastened by fasteners 23 upon a bearing 24 built with the arm A and projected outwardly from one face 25 thereof.

Intermediate of the spring 22 is an adjusting screw 25 which is loosely passed through a suitable opening therefor in said spring and is threaded in a socket 26 in the arm 10 to vary the tension of the said spring. Thus by the pivot lug 21 the blade 16 is hung for swinging movement with relation to the arm 10, the said blade 16 being provided with a dished area 27 which places the cutting edge 18 in close relation to the bill 14 of the hook 13 for assuring a positive cutting action in the working of the attachment. The blade 16 has fitted in its notch 17 a pivot stud 28 on a control rod 29 so that the said blade will be operated for opening and closing movements under the approach and receding of the hook 13 to and from the work in the working of the sewing machine and under such movements the bill 14 of the hook will enter the loop of the thread looped by the sewing machine to hold such loop whereby the blade 16 will sever it for tufting work in the forming of pile thereon.

The spring 22 will allow for the easy removal of the blade 16 which is hung pivotally by said spring in working relation to the hook 13 so 55

that such blade can be replaced, sharpened or properly conditioned for the successful working of the attachment in tufting work with the use of the attachment in a heavy duty sewing machine.

6 The loop of the thread under the operation of the sewing machine is carried forth downwardly through a piece of fabric and the loops of thread each is caught by the hook 13 and such loop is severed by the blade 16 for pile forming in a single operation of the sewing machine.

What is claimed is:

1. A tufting attachment for a sewing machine having a stationary pivot bolt for an oscillatory member and also provided with a reciprocatory control bar, comprising an oscillatory stroke arm journaled on said bolt and having a transverse recess at the end remote from said bolt, a loop engaging hook releasably seated in said recess, 10 an opening and closing cutter blade cooperating with said hook and pivoted to the arm, a leaf spring having one end fixed to said arm and its other end releasably pivoted to said blade, a connection between said control bar and said 15 blade, and an adjusting screw loosely passed

through the spring intermediate thereof and engaged in the arm.

2. A tufting attachment for a sewing machine having a stationary pivot bolt for an oscillatory member and also provided with a reciprocatory control bar, comprising an oscillatory stroke arm journaled on said bolt and having a transverse recess at the end remote from said bolt, a loop engaging hook releasably seated in said recess, 10 an opening and closing cutter blade cooperating with said hook and pivoted to the arm, a leaf spring having one end fixed to said arm and its other end releasably pivoted to said blade, a connection between said control bar and said 15 blade, an adjusting screw loosely passed through the spring intermediate thereof and engaged in the arm, said blade being tapered in one direction with its narrow end connected with said bar, a beveled cutting edge formed on the wider end of the blade next to the bill and extended 20 for a distance to effect a blunt heel portion, and an outwardly dished area formed on the blade next to said cutting edge for placing the latter in close relation to the bill of the hook.

BOYD N. CAGLE.
